UNITED STATES PATENT OFFICE.

CLARENCE W. UTZMAN, OF CHICAGO, ILLINOIS, ASSIGNOR TO UNITED STATES GYPSUM COMPANY, OF CHICAGO, ILLINOIS, A CORPORATION OF ILLINOIS.

BOUND-EDGE PLASTER WALL BOARD.

Original application filed March 14, 1923, Serial No. 624,931. Patent No. 1,540,045, dated June 2, 1925.
Divided and this application filed November 17, 1924. Serial No. 750,224.

This invention relates to building material and more particularly to an improved bound edge plaster wallboard.

Plaster board in building construction has been used for a long time as a substitute for wooden laths or the like in the erection of walls and ceilings and, having been nailed or otherwise secured to the studding or held in position, is given the usual coats of plaster to surface the wall or ceiling. At first such plaster board was constructed in flat sheets having a plaster or similar composition core with paper or fibrous material applied on each flat surface as a protective covering which also gave sufficient tensile strength to the core to maintain its conformation during the handling necessary in transportation and erection. Plaster board of this character varied in thickness and dimensions usually 36" long by 32" wide, as the standard width between centers of studs is customarily 16". Sizes of greater width and length were impracticable as the cover sheets would peel back and become torn in handling until the problem was solved by binding the longitudinal edges of the board as set forth in my Patent 1,034,746 of August 6, 1912. After this discovery plaster panel or wallboard came into vogue and could be fabricated in 48" widths and of a length to reach from ceiling to floor and in the development of plaster panel board it was found that it could be made sufficiently smooth of surface and thick enough to obviate the necessity of the heretofore usual coating of plaster so that the present plaster wallboard can be applied directly to the studding and provides a finished surface ready for decorating.

This invention relates to improvements in plaster wallboard and is a division of my prior application Ser. No. 624,931 filed March 14, 1923, Patent No. 1,540,045, June 2, 1925. It contemplates the production of a plaster wallboard of uniform thickness throughout and in which the edges of the margins of the cover sheet brought about the longitudinal edges of the composition core will not project above nor cause the other cover sheet at its longitudinal margins to project above the main body of that side. This invention also contemplates the binding of the edge in such a manner that while the

thickness of the board remains constant throughout, the longitudinal edges may be 55 formed flat and at any angle to the flat main surfaces of the board desired, as well as providing means whereby the outer cover sheet may be brought substantially flush with the longitudinal edges and lie in the plane of 60 the surface on that side on which it terminates.

The advantages of this particular construction of plaster wallboard will be pointed out as the different forms are described. 65 With these and other objects in view, reference is had to the accompanying sheets of drawing, which illustrate the preferred forms of this invention with the understanding that minor detail changes may be made 70 without departing from the scope thereof, and in which like reference characters indicate like parts.

Figure 1 is a view in perspective, illustrating a transverse edge in section, of one 75 form of this invention.

Figure 2 is a view in transverse section, enlarged, of Figure 1.

Figure 3 is a top plan view, with parts broken away, of the edge portion of Figure 1. 80

Figure 4 is a view in perspective of another form of this invention.

Figure 5 is a view in transverse section, enlarged, taken at one edge of Figure 4. 85

In practicing the inventions set forth in my Patents 1,034,746 of August 6, 1912 and 1,029,328 of June 11, 1912, with the heavier chip paper usually employed in the two ply panel or wallboard it has been found that 90 the board leaves the compression or forming roll in the form shown in Figure 6 of Patent 1,029,328, that is with the edge of the side margins of the top sheet resting upon and projecting above the inturned edge of the 95 lower covering sheet and the upper face of the top covering sheet is not forced down flush with the upper faces of the inturned laps as shown in Figure 2 of Patent 1,034,746, as is accomplished with the thinner felt paper used in fabricating the four 100 ply plaster board illustrated in these patents. The result is that with the heavier chip paper, when the top covering sheet is applied as the board passes under the forming roll, the inturned edge embracing flaps 105

of the bottom sheet are of such stiffness that they are angularly depressed from the bend at the top corner of the edge, when the edges are scored to form the corners as set forth in my Patents 1,330,413 of February 10, 1920 and 1,383,249 of June 28, 1921, although the upper corner itself lies in the plane of the upper surface of the top cover sheet there is a slight depression along each longitudinal edge deepening from the corner of the edge of the board to the bottom of the longitudinal edge of the top sheet, which depression varies in width in accordance with the slight variations of the position of the top cover sheet caused by the variations of the width of the paper and the slight weaving of the paper in the machine before it is applied to the board.

On account of these depressions along each longitudinal edge the top sheet side of the board must be applied next to the studding to present a smooth exterior surface to the wall or ceiling. It has also been found in the practical manufacture of plaster wallboard in accordance with patents heretofore mentioned that the consistency of the plastic mixture for the core due to mechanical limitations of machinery at times is thicker than at other times, which results in the plastic core mass not uniformly and completely entering between the top of the folded over flap and under side of the longitudinal margin of the top cover sheet as the board passes under the forming roll and smoothing or ironing devices thereafter and also at times causes the edge of the top sheet to project above the adjacent upper corner of the edge of the board. The effect of this is that there are hollow spaces left between the covering sheets under the margins adjacent the edges of the top sheet so that when the wallboard is applied with the top cover sheet side against the stud and nailed thereto, the driving of the nail through such hollow spaces causes the margin of the wallboard at that point to be drawn against the stud below the exterior surface of the adjacent wallboard and at times bends the margin at such edge for a substantial distance causing a depression abutting the uniform edge of the adjacent wallboard upon the exterior wall surface.

This invention contemplates various related means for producing plaster wallboard that will be of uniform thickness throughout, that is the exterior dimension of thickness will be the same throughout each longitudinal bound edge of each wallboard so that all portions of each side surface will lie in the same respective plane. In such a wallboard either side may form the exterior of the wall and it will not be necessary to place one particular side against the studding and as each longitudinal edge when nailed to the studding will uniformly

engage the stud throughout so that the exterior surfaces of the abutting edges of adjacent wallboards will lie in the same plane and the surface of the entire wall although made up of sections of wallboard will be uniformly smooth.

One form of this invention is illustrated in Figure 1 in which the bottom cover sheet 1 is folded to envelop the longitudinal edges of the plastic composition core 2 with the margins 3 of the edges of this sheet lying upon the top of the core, and the top cover sheet 4 is of sufficient width to be folded about the longitudinal covered edges of the wallboard to embrace the margins of the bottom cover sheet and be secured thereto. It is preferable to score the bottom sheet along the lines where the bends in the folds of the margins form the corners of the board before the top sheet is applied and it is also preferable to score the top sheet along the lines where its margins fold over the core edge enveloping portions of the bottom sheet to provide square corners. It is preferable to accomplish this scoring of the top cover sheet just before it is applied to the wallboard so that there will be an exact register with the corners of the bottom sheet when the top sheet is folded thereover. The margins 6 to the top sheet are chamfered or beveled so that they taper from the bottom corner scorings to their respective edges. The scorings are so arranged on each side of the bottom sheet that the corresponding scorings of the top sheet will fold about the edges and will be the desired thickness of the wallboard.

It is preferable to apply the top sheet and fold its margins about the longitudinal edges before subjecting the wallboard with its core in plastic condition to the final pressure that determines and maintains the uniform thickness, which pressure will also align the folded over margins of the top sheet in the same plane with the main portion of the bottom sheet. The portions of the top sheet contacting with portions of the bottom sheet may be secured or bonded thereto throughout the contact or any portion thereof by a film of the plastic body material or by an adhesive, such as silicate or soda, or by a combination of both. As aforesaid, it is preferable to accomplish the scoring of the top sheet just before it is applied, it is also preferable to chamfer or bevel the margins of the top sheet at the same time or just after the scoring so that the margins will taper from the outer scored lines to their respective edges, and variations in the width of the paper will not effect the finished wallboard because the scorings of the top and bottom sheets are so arranged that the outer top sheet will embrace the corners of the bottom sheet fold and the final pressure in applying the taper.

ing margins of the top sheet on the under side of the bottom sheet will cause the angular portions 6 adjacent the innermost scoring of the bottom sheet to be adjusted in accordance with the amount of top sheet margin applied thereover. If it is desired to maintain the margins 3 of the bottom sheet against the under portions of the enveloping top sheet, the margins may be slit preferably at right angles to the edges sufficiently to form tongues 7 bent at right angles thereto and which will enter the composition body as the margins are folded down thereover and prevent the folded over portions becoming depressed into the plastic core. In this form of this invention the wallboard is reversible, will engage the stud throughout its longitudinal edge, and possesses doubly protected longitudinal edges 20 and edge corners.

A modification is shown in Figures 4 and 5 in which the top cover sheet is cut wider than the desired width of the wall board. The top sheet is scored preferably just before the sheet is applied to the plastic core after the margins 3 of bottom cover sheet 1 have been folded over to lie upon the top of the core. The scoring of the top sheet forms the top corners of the longitudinal edges and is arranged above the scorings of the bottom sheet that forms the lower corners of the said edges. The margins 9 of the top sheet are chamfered or beveled so that they will taper from the scorings to their respective edges and when folded down against the edge covering the portion of the bottom sheet will form rectangular longitudinal edges upon the wallboard. The scorings upon the bottom sheet are so arranged that the outermost scorings will allow the bend within the top cover sheet to be made within the desired thickness of the wallboard. The contacting portions of the bottom and top sheets may be bonded or secured by a film of the plastic body material or by an applied adhesive throughout the entire contact or by any combination of these desired. This form of wallboard is reversible and of uniform thickness throughout and its appearance or effectiveness is not effected by the variations in width or weaving of the top sheet during manufacture.

I claim:

1. A plaster wallboard having a composition body with fibrous cover sheets thereon, one of said cover sheets passing about the longitudinal edges of the wallboard to engage the opposite side thereof with the other cover sheet extending about said edges over said first sheet to engage the opposite side and secured at its margins thereto, said margins chamfered to bring the exterior surfaces thereof into the plane of the main body of said first sheet, and the inner cover sheet being formed with spaced tongues

which extend transversely within the wallboard to support the opposite cover sheets at their edges.

2. A plaster wallboard having a composition body with fibrous cover sheets thereon, one of said cover sheets passing about the longitudinal edges of the wallboard to engage the opposite side thereof with the other cover sheet extending beyond the side it covers and passing onto the said edges with its margins secured to the first sheet, said margins chamfered to bring the exterior surfaces thereof into the plane of the other sheets, and a series of tongues formed in the edge of the inner cover sheet to extend transversely in the wallboard to strengthen the edges thereof.

3. A plaster wallboard having a composition body with fibrous cover sheets thereon, one of said cover sheets passing about the longitudinal edge of the wallboard with the margin engaging the opposite side thereof, and a series of tongues extending from the edge of one of the cover sheets within the composition body for supporting the cover sheet opposite said margin.

4. A plaster wallboard having the composition body with fibrous cover sheets thereon, one of said cover sheets passing about the longitudinal edge of the wallboard with the margin engaging the opposite side thereof, said margin provided with integral spaced means inwardly extending therefrom for supporting the opposite portion of the same sheet in contact with the other cover sheet.

5. A plaster wallboard having a composition body with fibrous cover sheets thereon, one of said cover sheets passing about the longitudinal edges of the wallboard with margins engaging the opposite side thereof with the other cover sheet extending about said edges over said first sheet to engage the opposite side and secured at its margins thereto, said margins of the first cover sheet being provided with tongues extending through the composition body to the main portion of that sheet to maintain said margins against the under side of the second cover sheet.

6. A plaster wallboard having a composition body with fibrous cover sheets, both of which extend about the longitudinal edges of the wallboard, the inner sheet having an integral portion comprising spaced tongues extending transversely within the composition body to support the opposite portion of the same sheet.

7. A plaster wallboard having a composition body with fibrous cover sheets, one of which passes about the longitudinal edge to engage the opposite side thereof and having integral spaced tongues extending from its edge within the wallboard to engage and support the portion of the same sheet which is on the opposite face of the wallboard.

8. A plaster wallboard having a composition body with fibrous cover sheets both of which extend about the longitudinal edges of the wallboard and overlap on opposite sides thereof, the inner sheet having integral tongues extending from its edge across within the composition body to engage and support the opposite portions of both sheets where they overlap.
10. 9. A plaster wallboard having a composition body with fibrous cover sheets both of which extend about the longitudinal edges of the wallboard and overlap on opposite sides thereof the inner sheet having integral tongues extending transversely within the composition body to engage the opposite portion of the same sheet forming a strut for strengthening the opposite portions of both sheets where they overlap, and the margins of the outer sheet being chamfered to bring the exterior surface thereof into the plane of the main body of the first sheet.

CLARENCE W. UTZMAN.
